UNITED STATES PATENT OFFICE.

JOSEPH MARTIN SCHUTZ, OF CHICAGO, ILLINOIS, ASSIGNOR TO SCHUTZ HAWLEY COMPANY, OF CHICAGO, ILLINOIS, A CORPORATION OF ILLINOIS.

SELF-CONTAINED PULVERIZING AND SEPARATING MILL.

1,305,413.

Specification of Letters Patent. Patented June 3, 1919.

Application filed July 22, 1915. Serial No. 41,340.

To all whom it may concern:

Be it known that I, JOSEPH MARTIN SCHUTZ, a citizen of the United States, residing at Chicago, in the county of Cook 5 and State of Illinois, have invented certain new and useful Improvements in Pulverizing and Collecting Apparatus Known as Self-Contained Pulverizing and Separating Mills, of which the following is a specification.

My invention relates to improvements in apparatus for pulverizing various materials and for separating or collecting the pulverized products. The invention has especially reference to improvements in means for continuously pulverizing and separating materials such as coal, limestone, talc, gypsum, clay, iron ore, chalk, paint rock, colors, graphite, marl, phosphates, borax, salt, 15 sugar, drugs, dyes, and both crystallized and oxidized minerals generally.

Many materials are capable of reduction by attrition mills, but I have found disintegration mills to have a wider range of usefulness and greater capacity. Such mills are characterized by hammers or beaters which are rotated at high speed and that set up air currents of large volume and high velocity. In such mills the air current is 20 depended upon to carry away the pulverized product and the final recovery of the material is accomplished by separating it from the vehicular air by means of cloth bags or settling chambers.

The greatest care does not suffice to prevent the loss of an annoyingly large part of the finest product. Another objection to disintegration mills is that they are difficult to adjust when it is desired to vary the 25 quality of the product or to change from one material or stock to another. Another drawback is that such mills, with their air trunks, piping and collectors, occupy a great deal of room. They also require constant 30 attention; and their collectors or separators must be cleaned frequently, else the flow of air is reduced and the capacity of the mill is cut down.

A primary object of my invention is to 35 provide a disintegration type pulverizing mill and separator in one and the same machine and so constructed that each shall form a part of and complete the other; whereby the above mentioned and other ob-

jectionable features of the ordinary apparatus may be overcome and eliminated.

Still further objects of my invention will appear hereinafter.

The preferred manner in which I attain this and other objects of the invention will be understood upon reference to the accompanying drawings, forming part of this specification, and in which:

Figure 1 is a side elevation of a self-contained pulverizing and separating mill, embodying my invention; Fig. 2 is an elevation of the discharge end of the mill; Fig. 3 is an elevation of the other, or driving end of the machine; Fig. 4 is transverse vertical section on the line 4—4 of Fig. 1; Fig. 5 is a longitudinal vertical section on the line 5—5 of Fig. 2; Fig. 6 is a longitudinal vertical section on the line 6—6 of Fig. 4; Fig. 7 is a plan view of the lower part of the mill as it appears when the upper part or separator is removed; Fig. 8 is a horizontal section on the line 8—8 of Fig. 2; Figs. 9, 10, 11, 12, 13 and 14 illustrate various modifications of my novel centrifugal separator; Fig. 15 is a vertical longitudinal section illustrating a modified form of my mill, the section being taken on the line 15—15 of Fig. 16 viewed in the direction of the arrow, 15^a; and Fig. 16 is a vertical transverse section of the mill on the line 16—16 of Fig. 15, viewed in the direction of the arrow 16^a.

In the preferred form of my invention shown in the drawings, my mill comprises a lower part and an upper part, and two air trunks that join them. The material is fed into the lower part and is there pulverized. The operation of the lower part of the mill sets up strong movements or currents of air that pass through one of the air trunks into the upper part of the mill and return from thence to the lower part. The whole pulverized product *i. e.*, both the fine and the coarse particles, pass from the lower to the upper part through the air trunk referred to. On entering the upper part of the mill the stream (of air and pulverized material) expands. I take advantage of the centrifugal action of the particles coupled with the expansion of the air to secure a separation of the fine from the coarse particles, and return the coarse particles or tailings to the lower part of the mill, prefer-

ably through the other air trunk. I construct the machine in such manner that the fine particles which are separated and collected in the upper part of the mill may be 5 discharged in a solid stream, substantially free from air; or when desired the fine material may be air-floated from the upper part of the mill and discharged into ordinary collectors. From the description 10 which follows, it will also be apparent that I may employ my machine for the centrifugal separation of one grade of material and for the air-flotation of the finer grades. By very simple means I provide for the 15 regulation and control of the quality of the pulverized product, and provide for the adjustment of the machine without interrupting its operation.

Referring now to Figs. 1 to 7, inclusive, 20 it will be seen that the lower part of my machine is in the form of a cylinder, having a horizontal axis occupied by the main shaft, 2. The ends of the cylinder contain central openings, 3, for purposes to be described. 25 The cylinder is parted upon a vertical plane which includes its axis. One-half, a , is preferably cast integrally with the feed chute, a' , and is permanently fastened to the base, b . The other half, a^2 , is secured to 30 the base and to the part, a , by means of bolts, 4, and when these are removed the part, a^2 , may be taken off the base, as required to clean the machine or repair the parts in the drum. The bottom of the drum 35 contains a preferably corrugated lining made in two parts, 5 and 6. These parts are held in place by the deflecting plate, 7, of the feed chute, and by the locking plate, 7', in the part, a^2 . A feed hopper, 8, is placed 40 on the chute and contains a feed roll, 9. 10 is the feed adjustment plate of the feed hopper.

It will be noted that the cylinder, $a-a^2$, is provided with two upwardly extending 45 tangential ducts, 11 and 12. The duct, 11, rises from the side of the drum opposite the feed chute; and, the duct, 12, opens downwardly into the feed chute, directly above the deflecting plate, 7.

50 The shaft, 2, is carried by the pillow blocks, b' , b'' , on the base, b , and is driven by a belt (not shown) on the pulleys, 2'. Within the cylinder or drum, $a-a^2$, the shaft is provided with a series of collars, 14, 55 which are keyed thereto and serve as the mountings for the hammers or beaters, 15, which preferably are pivotally attached thereto, as shown. There are many of these hammers and when the shaft is rotated in 60 the direction of the arrows in Fig. 4, they forcibly break and disintegrate the material which enters through the feed chute, 4. Their operation in connection with an ap- 65 posed corrugated wall like that shown here- in is now too well understood to require de-

tailed explanation. It is sufficient to say, that in rotating they perform the double purpose of breaking up the material and setting up currents of air by which the material is discharged or expelled from the mill. 70 They operate to draw air into the cylinder and discharge the same and the material at high velocity through the tangential outlet and duct, 11.

Before passing on to the consideration of 75 the means which I employ for separating the pulverized material from the vehicular air and for separating the fine from the coarse material, it should be noted that my pulverizing mill is most convenient in that 80 it may be easily cleaned and repaired. For that purpose it is unnecessary to remove the ends of the pulverizing cylinder, for the whole side, a^2 , may be removed without disturbing any other part. When the machine 85 is opened in this way the beaters are accessible and obviously the linings may be removed and replaced and the whole interior thoroughly and quickly cleaned and repaired with little delay and effort. 90

The ducts, 11 and 12, are preferably (though as shown in Figs. 15 and 16 not necessarily) of the same length as the pulverizing cylinder. They are the lower ends 95 of the air trunks referred to above, and serve to join the pulverizing cylinder with the separating cylinder or drum, c . Thus, as shown in Figs. 1 to 8, d and e are the air trunks, and those as shown are tangentially positioned with respect to the drum, c . The 10 drum, c , is preferably of the same length as the drum, $a-a^2$, and the air trunks d and e are preferably of the same cross section as 11 and 12. I prefer that the parts or legs, 11' and 12', shall be formed in the same 10 casting with the drum, c , and when necessary the whole top may be lifted off as one part.

The ends of the separating drum, c , are closed by plates, c' , and c^2 , and these contain 11 central openings of sizes determined by the character of the work to be done, as hereinafter described. Thus, as shown in Figs. 1 to 8, the plates c^1 , c^2 , contain relatively small openings, c^3 , which are placed in communication with the openings, 3, 3, of the pulverizing cylinder by means of pressure relief or down ducts, 16, 16. The down ducts are connected with the openings, 3, through the medium of preferably conical cavities, 12, 16', in the ends of the pulverizing drum, as well shown in Fig. 5. Valves, 16^a, located in those portions of the down ducts within the pulverizing mill, provide for the easy control of the pressure at the axes of the 12 separating drum, and supplement the action of the skimmer hereinafter described.

Referring to Fig. 4 it will be seen that the bottom c^a , of the drum, c , is preferably formed on a shorter radius than the top 13

and sides of the drum and merges with the inner walls of the air ducts, *d* and *e*. The bottom contains a longitudinal and horizontal slot, 17, adjacent its juncture with the inner wall of the trunk, *d*. This slot communicates with a valve and conveyer casing, 18. The casing contains a rotary valve, 19, and a conveyer, 20. It is open at one end of the conveyer, as shown in Fig. 6. A discharge device is applied at this point, the same comprising a head, 21, secured to the plate, *c*², and having a short spout, 21'. 5

At the juncture of the bottom, *c*^a, and the inner wall of the air trunk, *e*, I place a deflecting valve or skimmer, 22, securing same by means of a horizontal, longitudinal shaft, 23, journaled in the ends of drum, *c*. One end of the valve shaft, 23, is equipped with an adjusting lever, 24, and a quadrant and 20 set screw, 25, are provided for securing the lever, 24, and the skimmer, 22, in determined positions.

The shafts, 19' and 20', of valve 19 and conveyer, 20, respectively, are held in suitable stuffing boxes and bearings, 26, and at one end are connected by gears, 27, which provide for the rotation of the valve at higher speed than the conveyer. A large pulley, 28, on the shaft, 19, is connected with 30 the small pulley, 29, on the shaft, 2, by means of a belt, 30; and obviously the valve and conveyer operate continuously as long as the beaters are in operation. As a convenient means of driving the feed roll, 9, I employ 35 a ratchet mechanism, 31, connected to crank, 27', on the larger gear, 27, as by means of a rod, 32.

The operation of the mill, assuming the main shaft and beaters, and the valve, the 40 conveyer and the feed roll to be in rotation, is as follows:—

The material which falls from the roll, 9, passes into the pulverizing cylinder, *a*—*a*², and is there attacked and disintegrated by 45 the beaters and finally driven and carried upward through the air trunk, *d*. Thus both large and small particles of material and a large volume of air under considerable pressure enter the separating and collecting 50 drum, *c*, at very high velocity. The particles are flung against the periphery of the drum, *c*, and sweep across the same toward the skimmer, 22. The heavier particles or tailings naturally follow the wall and descending through the trunk, *e*, are forcibly impelled against the plate, 7. On striking 55 the plate the material is deflected inward against the beaters, joining the flow from the feeder.

60 The air on emerging from the trunk, *d*, expands, and a considerable part of the stream, carrying the finer particles of material, strikes and is deflected by the valve or skimmer, 22. Thereby, the particles of 65 material are projected against the skimmer

and the bottom, *c*^a, of the drum, and sweep into the slot, 17. By reason of the presence of the valve, 19, the slot obviously opens into a dead air space, and hence the fine material is deposited upon the valve and is discharged upon the conveyer, 20, which ultimately expels the material in the form of a solid stream at the spout, 21'. 70

As the air removed from the main stream by the skimmer whirling within the drum, 75 *c*, cannot find escape at the slot, 17, it ultimately frees itself from practically all of the fine material or dust and escapes through the central relief opening, *c*³, and the down ducts, 16, thus re-entering the pulverizing 80 mill. When desired, a nice adjustment of the pressure of air at the relief openings, *c*³, may be secured by means of the valves or dampers 16^a in the down ducts; and when a skimmer is not used, these valves, 16^a, constitute the best means of regulation. It will 85 be clear that the rotating beaters draw the air through the down ducts. By this means I maintain a lower pressure at the axis at the drum, *c*, than at its periphery, and effectually insure the rapid separation of the fine from the coarse material. By this means also I make it possible to limit the volume of air handled by the machine to that required 90 to fill the air belt constituted by two drums and the two air trunks, plus the down ducts. Clearly, the only fresh air that need enter through the feed hopper is measured by the small quantity which is discharged through 95 the valve casing, 18. 100

By the mere act of changing the position of the skimmer or deflecting valve, 22, I am able to regulate the fineness or quality, of the product at the discharge spout, 21'. And by changing the position of one or both 105 valves, 16^a, a still finer separation may be attained.

Numerous modifications are made possible by the convenient form and relation of the separating drum and the air ducts. Several 110 of these modifications are disclosed in Figs. 9 to 14.

In Fig. 9 I have shown a structure differing from that above described, in that the drum contains an inner wall, *c*^x, having an 115 opening for the skimmer. In this form I make a double separation by retaining the discharge slot and valve, and adding larger central openings in the head of the drum, through which material may be floated to 120 the trunk or trunks, 33, leading to a suitable dust collector (not shown).

An arrangement limited to an air floated product is shown in Fig. 10; in which case 125 the pulverizer furnishes a constant supply of fresh air; and the return of the air to the mill is prevented by a rotary valve, 34, arranged in the return air trunk. It should be understood that when the separator shown in Fig. 10 is placed on the base mill, the 130

down ducts 16 of the latter are left open to receive air; and the necessary regulation is secured by adjusting the valves, 16^a, therein. This is also true in the cases of Figs. 9, 11 and 14.

In Fig. 11 I have shown another form of separator adapted to produce two grades of material; 35 being the air float trunk, and 36 being a tailings discharge duct, containing an air stoppage valve, 37.

That the discharge of the material may be accomplished in the central bottom portion of the drum, is clearly shown by Fig. 12. It may also be discharged at one side of 15 the drum, as shown in Fig. 13. Both Figs. 12 and 13 forms possess the advantage of having settling pockets, 38 and 39.

Fig. 13 also shows that the separator may be employed for separating the fine material 20 from the tailings without special regard to the relief and return of all of the air to the pulverizer. And as shown in Fig. 13 the air, which is separated from the main stream by the skimmer, finds direct relief at the 25 opening 39' which preferably contains a conveyer 39'', discharging into a suitable collector.

Fig. 14 illustrates a modified form of an air floating separator in which I employ a 30 precautionary by-pass, 40, containing a valve, 41, for ridding the bottom of the drum of material which might otherwise lodge therein. This is of particular advantage in handling moist materials.

Thus far I have described only that form 35 of my mill in which the air trunks are of the same cross sectional length as the pulverizing cylinder. There are some cases in which it is desirable to expose the material or stock 40 to the action of the beaters for a longer time. In such cases I prefer to modify the construction in the manner generally depicted in Figs. 15 and 16 where the material is fed to the beaters through a feed spout, 45 42, arranged on one end of the pulverizing cylinder, and the air belt 43 is limited to the opposite end of the pulverizing cylinder. In this case the air trunks are of less length than the drum, and this is also true of the 50 separating cylinder, 44. Except for the modified shapes of the air trunks and down ducts, 45, 46, this mill is substantially the same as the one before described and its principle of operation is substantially the 55 same.

I claim each and every of the following parts, improvements and combinations:

1. The improvement herein described comprising a rotary beater, in combination with 60 a co-acting shell surrounding the same and

having air-intake openings in its ends, a chute communicating with the interior of the shell and through which the material to be milled is fed, a tangential outlet for said shell, a reversely positioned tangential inlet therefor, a drum superimposed upon said shell and having air outlet openings in its ends and which are in communication with respective air-intake openings in the ends of said shell, said drum having a tangential 6 inlet which joins the tangential outlet of said shell and a tangential outlet which joins the tangential inlet of said shell, and means for continually removing material from said drum, substantially as described. 7

2. The improvement herein described comprising a rotary beater, in combination with a coacting shell surrounding the same, and having air-intake openings in its ends, a chute communicating with the interior of 8 the shell and through which the material to be milled is fed, a tangential outlet for said shell, a reversely positioned tangential inlet therefor, a drum superimposed upon said shell and having air outlet openings in its 8 ends and which are in communication with respective air-intake openings in the ends of said shell, said drum having a tangential inlet which joins the tangential outlet of said shell and a tangential outlet which 9 joins the tangential inlet of said shell, and an adjustable skimmer positioned at the tangential outlet of said drum for separating fine from coarse material, the former for removal from the drum and the latter 9 for return to said shell, substantially as described.

3. The improvement herein described comprising a rotary beater, in combination with a coacting shell surrounding the same, and 10 having air-intake openings in its ends, a chute communicating with the interior of the shell and through which the material to be milled is fed, a tangential outlet for said shell, a reversely positioned tangential inlet 10 therefor, a drum superimposed upon said shell and having air outlet openings in its ends and which are in communication with respective air-intake openings in the ends of said shell, said drum having a tangential 11 inlet which joins the tangential outlet of said shell and a tangential outlet which joins the tangential inlet of said shell, and means for controlling the return flow of air through the air passages which connect the 11 ends of the drum with the ends of the said shell, substantially as described.

In testimony whereof, I have hereunto set my hand, this 20th day of July, 1915.

JOSEPH MARTIN SCHUTZ.
